[57] CLAIM

The ornamental design for an automobile, as shown and
described.

DESCRIPTION

FIG. 1 is a perspective view of the front and left side of
an automobile showing my new design, the right side
being substantially a mirror image of the left side;
FIG. 2 is a perspective view of the rear and left side
thereof;

FIG. 3 is a top plan view thereof on a reduced scale;
FIG. 4 is a left side elevation view thereof on a reduced
scale;

FIG. 5 is a rear elevation view thereof on a reduced
scale;

FIG. 6 is a front elevation view thereof on a reduced
scale.

FIG. 1

FIG. 2

FIG. 5

FIG. 6

FIG. 3

FIG. 4
